Attorney

UNITED STATES PATENT OFFICE.

JOHN BRENNAN HINES, OF GUELPH, ONTARIO, CANADA.

SOLE FOR RUBBER BOOTS.

Application filed January 17, 1927. Serial No. 181,701.

The present invention relates generally to improvements in rubber boots for firemen and consists particularly of a puncture-proof inner sole for rubber foot-wear, with metal disks placed at certain intervals; with lining of the said foot-wear gummed so that the inside of the foot-wear will dry very quickly. The sole of the foot-wear is composed of three inter soles with perforations. 10 These perforations are so made on each of the three inter soles that when the three inter soles are placed in superposed relationship said metal disks which have been inserted in the perforations will make the soles puncture-proof. When the three inter soles are assembled they form a flexible sole absolutely puncture-proof. 15 Another important object of the invention lies in the provision of a sole of this nature which is comparatively simple in its construction, inexpensive to manufacture, thoroughly efficient and reliable for the purpose specified and otherwise well adapted to the purpose for which it is designed. 20 With the above and numerous other objects in view as will appear as the description proceeds, the invention resides in certain novel features of construction, and in the combination and arrangement of parts 25 as will be hereinafter more fully described and claimed.

In the drawing:

Figure 1 is a bottom plan view of the bottom sole section,

Fig. 2 is a similar view of the intermediate sole section,

Fig. 3 is a similar view to the top sole section,

Fig. 4 is an edge elevation of the sole with the sections assembled.

Referring to the drawings in detail it will be seen that the numeral 1 denotes the bottom sole section which is provided with a plurality of apertures or perforations 2 for receiving metallic disks 3.

The numeral 4 denotes the intermediate sole section which is provided with perforations 5 for receiving metal disks 6 and the apertures 5 and metal disks 6 are arranged 45 in staggered relation to the apertures 2 and metal disks 3 when the intermediate sole section 4 is superposed on the bottom sole

section 1. The numeral 7 denotes the top sole section which is provided with perforations 8 having therein metal disks 9 which are arranged in staggered relation to the perforations 5, metal disks 6, and the perforations 2 and metal disks 3 when the three sole sections are superimposed as is shown to advantage in Figure 4. In Fig. 4 the numeral 10 denotes the gummed intersole attached to the sole section. This enables the boot which has a gummed inner lining to be drained and immediately dried as the inside will have a smooth rubber finish similar to the outside.

It is thought that the construction, utility, and advantages of this invention will now be clearly understood without a more detailed description thereof. The present embodiment of the invention has been disclosed in detail merely by way of example since in actual practice it attains the features of advantage enumerated as desirable in the statement of the invention and the above description. It will be apparent that changes in the details of construction, and in the combination and arrangement of parts may be resorted to without departing from the spirit or scope of the invention as hereinafter claimed or sacrificing any of its advantages.

Having thus described my invention, what I claim as new is;

1. A sole of the class described comprising three super-imposed sole sections having perforations, and a plurality of metal disks, one in each perforation, the metal disks in the three sole sections being arranged in staggered relation so as to prevent the piercing of the sole when the sections are assembled.

2. A sole of the class described comprising three super-imposed sole sections having perforations, and a plurality of metal disks, one in each perforation, the metal disks in the three sole sections being arranged in staggered relation so as to prevent the piercing of the sole when the sections are assembled, the upper surface of the top sole section being gummed.

In testimony whereof I affix my signature.

JOHN BRENNAN HINES.
